CLAIM

The ornamental design for a chair cover, as shown and described.

DESCRIPTION

FIG. 1 is a front/left perspective view of a chair cover according to my new design;

FIG. 2 is a front/right perspective view thereof;

FIG. 3 is a rear/right perspective view thereof;

FIG. 4 is a rear/left perspective view thereof;

FIG. 5 is a front view thereof;

FIG. 6 is a rear view thereof;

FIG. 7 is a right-side view thereof;

FIG. 8 is a left-side view thereof;

FIG. 9 is a top view thereof; and,

FIG. 10 is a bottom view thereof.

The broken lines and lightened, de-emphasized areas within the broken lines illustrate portions of the chair cover that form no part of the claimed design.

1 Claim, 10 Drawing Sheets
